UNITED STATES PATENT OFFICE.

CHARLES R. HARRY, OF FREDERICKTOWN, OHIO, ASSIGNOR TO THE J. B. FOOTE FOUNDRY COMPANY, OF FREDERICKTOWN, OHIO, A CORPORATION OF OHIO.

MACHINE FOR TAMPING CONCRETE.

Application filed July 22, 1921. Serial No. 486,792.

To all whom it may concern:

Be it known that I, CHARLES R. HARRY, a citizen of the United States, residing at Fredericktown, in the county of Knox and State of Ohio, have invented certain new and useful Improvements in Machines for Tamping Concrete, of which the following is a specification.

My invention relates to machines for tamping concrete in molds, particularly molds for making concrete blocks, although the machine is not limited in its functions to that particular purpose.

An object of my invention is to provide a machine of the character referred to which will be simple and economical in its construction and effective in its operation.

Referring to the drawings:

Fig. 1 is a top plan of a machine embodying my improvements.

Fig. 2 is a side elevation of the same.

Fig. 3 is a view of the opposite side from that shown in Fig. 2.

Fig. 4 is an enlarged plan view of a portion of one of the lifter arms and its co-operating cam.

Fig. 5 is a side elevation of the same.

Fig. 6 is a front elevation of the machine.

Fig. 7 is an enlarged front view of a portion of the guide bars and one of the lifter plungers and its lifter arm.

Fig. 8 is a section on the line 8—8 of Fig. 7.

Fig. 9 is a section on the line 9—9 of Fig. 7.

Referring to the drawings, a main supporting frame is provided consisting of four vertical legs 1, upper side rails 2, lower longitudinal connecting strips 3, and front and rear cross-straps 4 and 5. The frame thus constructed is braced by diagonal side strips 6 on both sides of the structure, similar diagonal strips 7, at the front and rear, and horizontally-extending diagonal strips 8 (Fig. 1) near the lower ends of the legs. The lower ends of the legs are connected to longitudinal base strips 9, which are extended forwardly a suitable distance and have their extensions connected by a sheet-metal floor 10.

The tamping members are three in number in the present machine, each consisting of a plunger formed of two parallel bars 11, spaced apart and connected together by spacing blocks 12 and 13 and bolts 14 at

their upper end and intermediate portion, and at their lower ends by the shanks 15 of tamping feet 16. The tamping members thus formed are slidably mounted between guide blocks 17, clamped between two parts 60 of horizontal bars 18.

The bars of one pair are connected to the bars of the other pair by vertical end standards 19, and further braced by the diagonal straps 20. This guide structure for the 65 plunger is supported at the forward end of the main frame by brackets 21, to which the side standards 19 are rigidly connected, the brackets being supported on the main frame through connections with blocks 22 70 and 23; the structure being further braced by strap 24 connecting the lower ends of the standards with the main frame.

Provision is made for consecutively raising and dropping the tamping members by 75 means of cam operated lifter arms, each of which is formed of two parallel bars 25. The rear ends of the bars of each arm are connected to a crank arm, 26, mounted to oscillate on a rod 27 supported by the blocks 80 23, the crank arm having a plurality of points of attachment for the bars 25 for adjustment purposes. The forward ends of the bars 25 are connected to extensions 13^a of the blocks 13 of the tamping members, 85 by the bolt 28 (see Fig. 9).

Mounted to rotate in the bearings 23 is a cam-shaft 29, carrying a series of three cam fingers 30, one for each lifter arm; the high points of the cams being at the extreme 90 ends of the fingers. The cam shaft is drawn from a main drive shaft 31 through the medium of sprocket-wheels 32 and 33 and chain 34; the drive shaft having a pulley 35. Each pair of bars 25 has a roller 36 to co-operate 95 with its corresponding cam-finger.

Extending beneath the series of lifter arm is a lifting rod 37 having a central crank-shaped portion 37^a. This rod is journaled in bearings 38 on the brackets 21 and one 100 end thereof has a lever 39 provided with a weight 40.

Supported on the cross frame member 4 is an inclined chute 41, the lower end of which terminates adjacent the tamping 105 members.

In order that the extent of downward movement of the plungers relatively to the mold may be varied, the bars 11 are provided with a series of openings 41 (Fig. 7) 110

to receive the bolt 14 so that the bars may be attached at different points to the block 13. To compensate for this adjustment each of the crank arms has a plurality of openings 26^a so that the lifter arms 25 may be connected therewith at different points.

The operation of the device is as follows: Power being applied to the pulley 35, the cam shaft 29 is rotated counterclockwise as viewed in Fig. 3. The cams being disposed equidistant about the shaft alternatively raise the lifter arms 25 and as soon as the rolls 36 reach the ends of the cams, the arms and plungers drop by gravity. The mold 10 is set beneath the plungers upon the floor 10 and the concrete is fed from any suitable source into the trough 41 so as to fall into the mold. To facilitate the placing of the mold in position all of the lifter arms and their connected plungers may be raised by depressing the lever 39. The plungers are

limited to their downward movement by the contact of the blocks 13 with the cross-bars 18 and the extent to which the feet 16 project into the mold is varied by the different points of attachment for the plunger bars 11 to the blocks 13.

Having thus described my invention, I claim:

In a machine of the character described, a series of vertically movable plungers having tamping feet, a series of lifter arms, means for adjustably connecting the forward ends of said lifter arms to said plungers, pivoted crank arms to which the rear ends of said lifter arms are adjustably connected, and means for alternately raising said lifting arms and their connected plungers and permitting them to drop by gravity.

In testimony whereof, I have hereunto set my hand this 19 day of July, 1921.

CHARLES R. HARRY.
